CUSHIONED HANDLE FOR PORTABLE
PERCUSSIVE TOOLSFrank J. Horvath, Cleveland, Ohio, assignor to
The Cleveland Pneumatic Tool Company,
Cleveland, Ohio, a corporation of Ohio

Application December 22, 1945, Serial No. 636,699

4 Claims. (Cl. 121—36)

1

The present invention relates to impact type tools and, more particularly, to portable pneumatic tools of the reciprocating plunger or hammer type.

Impact type tools vibrate considerably during operation. This is particularly true of pressure fluid operated tools of the reciprocating plunger or hammer type. In tools of this character the force of the pressure fluid which reciprocates the plunger acts equally upon the ends of the cylinder but in an opposite direction to that in which it acts upon the plunger. This tends to reciprocate the cylinder producing vibrations and shock which are normally transmitted directly to the tool mounting or support, which in the case of a hand held tool, is the hand or hands of the operator.

One of the principal objects of the invention is the provision of a novel and improved impact tool of the pressure fluid operated type comprising shock absorbing means interposed between the motor or impact producing mechanism and the support or handle of the tool.

Another object of the invention is the provision of a novel and improved impact tool of the pressure fluid operated, reciprocating plunger or hammer type comprising fluid shock absorbing means interposed between the motor or impact producing mechanism and the support or handle of the tool.

Another object of the invention is the provision of a novel and improved hand held impact tool of the pressure fluid reciprocating plunger or hammer type having fluid shock absorbing means interposed between the motor or impact producing mechanism proper and the handle of the tool.

The invention resides in certain constructions and combinations and arrangements of parts and further objects and advantages thereof will be apparent to those skilled in the art to which it relates from the following description of the preferred embodiment described with reference to the accompanying drawing forming a part of this specification, in which similar reference characters designate corresponding parts throughout the several views, and in which

Fig. 1 is a longitudinal sectional view, with portions in elevation, of a pneumatic tool embodying the invention;

Fig. 2 is an enlarged fragmentary sectional view taken approximately on the line 2—2 of Fig. 1;

Fig. 3 is a fragmentary sectional view taken approximately on the line 3—3 of Fig. 2;

2

Fig. 4 is a transverse sectional view taken approximately on the line 4—4 of Fig. 1;

Fig. 5 is a fragmentary sectional view approximately on the line 5—5 of Fig. 4; and

Fig. 6 is an enlarged, fragmentary sectional view of a portion of Fig. 1 but showing a modified construction.

The invention is herein illustrated and described as embodied in a chipping hammer of a type manufactured by The Cleveland Pneumatic Tool Company of Cleveland, Ohio, however, it is to be understood that the invention is applicable to various types of devices other than the particular tool illustrated. For the most part, the tool shown is well-known in the art and only those parts which are necessary to a complete understanding of the invention are herein shown and described in detail.

Generally speaking, the tool shown comprises a motor or impact producing mechanism A including a cylinder or barrel member 10 having a plunger or hammer 11 reciprocably supported in the cylinder chamber 12; a handle assembly B including the handle proper 13; means including an automatic plate valve 14 and a throttle valve 15 for controlling the flow of pressure fluid to the cylinder chamber 12 to reciprocate the plunger 11; and means comprising a fluid shock absorber for operatively connecting the handle assembly to the motor assembly impact producing mechanism. In the embodiment shown, the handle assembly B is connected to the cylinder assembly of the motor A.

The cylinder assembly comprises a cup-shaped member 20 threaded onto the rear end of the cylinder member proper 10 and which serves to hold a valve block 21 and valve block cap 22 against the rear end or face of the cylinder member 10. The front face of the valve block 21 abuts the rear end of the cylinder member 10 and the rear face of the valve block cap 22 engages the bottom of the cup-shaped member 20. The valve block 21 and valve block cap 22 are maintained in proper alignment with each other and with the cylinder member 10 by a plurality of dowel pins, not shown. The automatic plate valve 14 is located in a suitable chamber 23 formed in a recess in the face of the valve block 21 adjacent to the valve block cap 22.

The cup-shaped member 20 is provided with a plurality of longitudinally spaced, radial, annular flanges 24, 25 on its exterior; a longitudinally extending, central aperture 26 in its closed end; and a transversely extending aperture 27 in the closed end bisecting the aperture 26 and a circular

chamber 28 in the bottom of the member. The outer ends of the transversely extending aperture 27 are closed by plugs 30, 31 welded or otherwise fixedly secured to the member 29. The member 29 is threadedly connected to the rear end of the cylinder member 10 and the two parts are locked together by a locking ring 32 located adjacent to the front end of the member 29 and slidably keyed or splined to the cylinder member 10. The locking ring 32 has internal splines in mesh with external splines on the cylinder member 10, and a plurality of teeth or jaws on the rear face thereof of which engage similar teeth or jaws on the forward face of the member 29. A spring 33 located underneath a fluid deflector ring 34 slidably supported on the exterior of the cylinder member 10 provides means for normally maintaining the teeth or splines on the rear face of the lock ring 32 in engagement with the teeth on the forward face of the member 29, thus normally locking the member 29 to the cylinder member 10 and preventing relative rotation therebetween. The forward end of the spring 33 is fixed to the cylinder member 10 while the rear end engages the inwardly extending flange at the rear end of the deflector ring 34, which flange in turn engages the forward face of the locking ring 32.

The throttle valve 15 is slidably supported in a tubular member 35 fixed within an aperture 36 in the handle member 13. The valve 15 is adapted to be moved against a compression spring 37 interposed between the lower side of the valve 15 and a plug 38 closing the lower end of the member 35 by a plunger 40 also slidably supported in the handle proper 13. The plunger 40 is adapted to be depressed to open the throttle valve 15 by a throttle lever 41 pivotally supported in a recess or aperture 42 in the handle 13. The handle 13 is provided with a suitable connection 43 for attaching the tool to a source of pressure fluid. The connection 43 is threaded into an aperture 44 in the handle 13, which aperture is in continuous communication with an annular chamber 45 by a conduit 46 in the handle. The chamber 45 surrounds the member 35 intermediate its ends and is in communication with the outer ends of a plurality of apertures 47 extending through the wall of the member 35 below the seat for the throttle valve 15.

Upon being depressed, the throttle lever 41 opens the throttle valve 15 to admit pressure fluid from the annular chamber 45 to the aperture 36 by way of the apertures 47 and the interior bore 48 of the member 35. From the chamber 36 the fluid pressure is directed by a passage 53 to the transversely extending aperture 27 and the chamber 28 in the cup-shaped member 29. The passage 53 in the handle member 13 terminates in a central boss 51 projecting into the bottom of a cylindrical aperture 52 in the member 13 formed by an annular casing 53 concentric with the cylinder member 10, and into which aperture the rear end of the motor assembly A projects. As will be hereinafter apparent, the motor assembly reciprocates with respect to the handle assembly during operation of the tool and the aperture 26 in the closed end of the member 29 has a recess therein for the reception of a packing ring 54 for preventing the escape of pressure fluid through the aperture 26 and around the boss 51. From the aperture 27 pressure fluid is directed by an annular chamber 55 about the periphery of the valve block 21 and the valve block cap 22 and a radial passage 56 in the valve block 21, the outer end of which communicates with said

chamber 55, to an annular groove 57 in the valve block 21 at the forward side of the automatic plate valve 14. Pressure fluid is also directed from the aperture 27, by a passage 58 in the valve block cap 22, to an annular groove 60 at the rear side of the automatic plate valve 14.

With the parts in the position shown in Fig. 1, the plunger or hammer 11 has just completed its forward or power stroke. The automatic valve is in its forward position and pressure fluid is being admitted to that part of the chamber 23 to the rear of the valve 14 through the passage 58, etc. From the chamber 23 it is directed to the forward end of the cylinder chamber 12 to cause the plunger 11 to execute its return stroke by communicating passages 61, 62, 63 in the valve block cap 22, the valve block 21 and the cylinder member 10, respectively. The passage 63 extends longitudinally of the cylinder member 10 and opens into the forward end of the cylinder chamber 12 and pressure fluid directed thereby to the forward end of the chamber 12 will drive the plunger or hammer 11 toward the rear end of the chamber. The rate of flow of pressure fluid from the passage 58 to the passage 61 and in turn to the forward end of the chamber 12 is metered or determined by the space between the valve 14 and the end of the annular flange formed by the annular groove 60 and the longitudinal part of the passage 61 at the center of the valve block cap.

As the plunger 11 moves toward the rear end of the cylinder chamber 12, it closes an exhaust port 66, which had previously been opened by the forward movement of the plunger, to permit the exhausting of the pressure fluid behind the plunger 11 during the power stroke. Continued movement of the plunger 11 toward the rear opens an exhaust port 67 located forwardly of the exhaust port 66. The exhaust ports 66 and 67 are in communication with a longitudinally extending passage 68 in the cylinder member 10, which passage is in turn open to atmosphere through a plurality of radial apertures 70 in the cylinder member 10 located underneath the deflector ring 34. From underneath the deflector ring 34, the pressure fluid escapes through apertures 71 in the forward wall or flange of the deflector ring. Continued movement of the plunger 11 toward the rear after the port 66 has been closed causes the pressure of the fluid trapped in the rear part of the chamber 12 to increase until the pressure on the valve block or forward side of the valve 14 is sufficient to shift the valve 14 to the opposite side or end of the chamber 23. Attention is called to the fact that upon the opening of the exhaust port 67 the pressure on the rear or valve block side of the valve 14 dropped below line pressure.

Upon the shifting of the valve 14 to the rear part of the chamber 23, the flow of pressure fluid to the forward end of the cylinder chamber 12 is discontinued and pressure fluid is admitted to the rear end of the cylinder chamber 12 from the annular chamber 55 by a central, longitudinally extending aperture 72 in the valve block 21 through a metering arrangement similar to that previously existing at the rear side of the valve 14, and comprising the flange formed by the annular groove 57 and the aperture 72. Pressure fluid admitted to the rear end of the chamber 12 will drive the plunger or hammer 11 toward the forward end of the chamber 12 and into engagement with the rear face of the shank 73 of

is a chipping tool or steel. Prior to impacting the tool C, the plunger 11 will open the exhaust port 66 permitting the pressure fluid in the rear end of the cylinder chamber 12 to escape to atmosphere, however, the hammer 11 continues its forward movement until it strikes the tool. When the pressure in the rear part of the cylinder chamber 12 has decreased to such an extent that the pressure against the valve block side of the valve 14 is less than the pressure on the opposite side thereof, the valve will be automatically thrown to the position shown in Fig. 1 and the cycle of operation repeated. Tools of the character referred to usually have operating cycles of from 2000 to 3000 strokes per minute.

The rear end of the cylinder or motor assembly is resiliently held in the aperture 52 by a resilient, annular member 80 interposed between the rear face of the cup-shaped member 20 and the bottom of the aperture 52, and a resilient, annular member 81 interposed between the front face of the flange 24 on the member 20 and the rear face of a flange 82 on a nut-like member 83 threaded onto the forward end of the flange 53. In the embodiment shown, the members 80, 81 are composed of soft rubber or rubber-like material, however, any suitable resilient member or material may be employed. Any suitable means may be employed for locking the nut 83 onto the casing 53. As shown this is accomplished by one or more small setscrews 84 located at the joint between the nut and handle member 13. The resilient members 80, 81 permit limited movement of the cylinder assembly within the handle assembly longitudinally of the cylinder chamber 12.

Relative rotation between the cylinder assembly and the handle assembly is prevented by a plurality of locking segments 85, see Figs. 2 and 3, located in an annular chamber 86 between the rear end of the member 20 and the rearward periphery of the casing 53 of the handle member 13. The segments 85 are fixed relative to the member 20 by being held in engagement with the rear face of the annular flange 25 by the resilient member 80. The members 85 are provided with internal splines 87 extending the entire length thereof and which engage suitable splines in the rear end of the member 20 and with relatively short, external splines 88 which engage within elongated, internal splines 90 in the handle member 13.

In order to assist the resilient members 80, 81 in absorbing the shock and vibrations produced by the motor or impacting mechanism and preventing their transmission to the handle proper, the handle assembly includes piston-like means in the form of an annular ring 91, hereinafter referred to as an absorber ring, located in the space intermediate the radial, annular flanges 24, 25 on the member 20 and fixed with respect to the handle 13 and the casing 53 against movement lengthwise of the tool by a plurality of radially spaced members 92 having grooves in their lower ends adapted to receive the ring 91. Each of the members 92 is provided with a shank 93 which projects into a suitable aperture in a hollow setscrew 94 threaded into tapped apertures in the casing 53. The setscrews 94 may be locked in any suitable manner. As shown they are drilled through their heads and have a safety wire 95 inserted therethrough. The absorber ring 91 must be of the split type to permit its installation over one of the flanges 24, 25 and, as shown, it is of the step-cut type and has its ends pinned together, after installation, by a pin 75 of the piston-like ring 91 allow a certain amount

96. Alternatively any suitable type of split ring may be employed, such as, one having a diagonal scarf joint.

In the embodiment illustrated in Figs. 1 to 5, the chamber 100 formed by the annular flanges 24, 25 and the internal wall of the casing 53 of the handle member 13 and within which chamber the absorber ring 91 is located, is in continuous communication with the chamber 55 around the exterior of the valve block 21 and valve block cap 22 by passages 101, 102. The passage 101 opens into the forward end of the chamber 100 and the passage 102 opens into the rear end of the chamber. The passage 101 communicates with the passage 102, which latter passage extends to the chamber 55.

Packing rings 103, 104 located in suitable grooves in the annular flanges 24, 25 prevent the escape of pressure fluid from the chamber 100, however, suitable apertures, not shown, are provided in the casing 53 in front of the flange 24 and to the rear of the flange 25 to permit the escape to atmosphere of any pressure fluid which leaks past the packing rings 103, 104. In a similar manner a port or passage 105 in the handle member 13 permits any pressure fluid which might leak by the packing ring 54 to escape from the bottom of the aperture 52.

The motor and handle assemblies are normally held by the resilient members 80, 81 in the position shown in Fig. 1, the former of which resilient members is considerably thicker so as to permit relatively greater movement of the cylinder assembly toward the rear of the tool since the rearward impetus of the cylinder assembly is greater than its forward impetus. Similar provision has also been made in the sliding joint between the projecting boss 51 and the member 20 and the length of the splines 87 at opposite sides of the external splines 88 on the member 85. For the same reason, the ring 91 is located slightly to the rear of the center of the chamber 100. The ring 91 is provided with a plurality of spaced, restricted apertures 106 extending therethrough and the pressure fluid in the chamber 100 cooperates with the ring 91 to assist in absorbing the shock produced by the reciprocation of the plunger or hammer 11 and to damp out the vibrations produced before they are transmitted to the handle proper. Opposite sides of the piston-like member or ring 91 have equal areas exposed to the action of the pressure fluid in the cylinder or chamber 100 and the construction and operation thereof are that of a double, equal acting fluid shock absorber.

An alternative construction is shown in Fig. 6. The tool shown therein is similar to that shown in Figs. 1 to 5 and described above, with the exception of the fact that the passages 101, 102 are omitted and the chamber 107 corresponding with the chamber 100 of the preferred embodiment filled with a light oil. The other parts of the device are duplicates of those shown in the preferred embodiment and are designated by the same reference characters.

It is believed that the operation of the device will be apparent from the foregoing description. Suffice it to say that the shock and vibrations produced by the plunger or hammer 11 are absorbed by a combined action of the resilient members 80, 81 and the double, equal acting fluid shock absorbing mechanism comprising the ring 91, etc. The restricted conduit means connecting the portions of the chamber at opposite sides of the piston-like ring 91 allow a certain amount

of fluid to flow from the chamber at one side of the ring to the other. The holes 103 through the piston-like ring 91 may be eliminated in the embodiment shown in Figs. 1 to 5 because opposite ends of the chamber 100 are connected by the conduits 101, 102 but in the embodiment shown in Fig. 6, the holes are essential and serve as a means for metering the flow of liquid from one part to the other of the chamber. As an alternative construction, the holes 103 could be replaced by a conduit in the cylinder assembly connecting opposite ends of the chamber 107.

From the foregoing description of the preferred embodiments, it will be apparent that the objects heretofore enumerated and others have been accomplished and that there has been provided a novel and improved tool of the impact type having improved means between the tool proper and the handle or support thereof for absorbing the shock produced during operation. While the preferred embodiments have been described in considerable detail, the invention is not limited to the particular construction shown and it is my intention to hereby cover all adaptations, modifications and uses thereof which come within the practice of those skilled in the art to which the invention relates and within the scope of the appended claims.

Having thus described my invention, I claim:

1. In a pressure fluid operated tool of the character referred to, the combination of a motor assembly, a supporting assembly for said motor assembly including a handle member formed with a casing fitted over one end portion of said motor assembly, means for operatively connecting said assemblies for relative longitudinal movement therebetween including a sliding joint between said motor assembly and casing, and double acting fluid shock absorbing means including a fluid containing annular chamber intermediate the ends of said sliding fit, and a piston-like member carried by said casing extending radially and inwardly therefrom into said chamber whereby shocks or vibrations produced by said motor assembly are absorbed before reaching said supporting assembly.

2. In a pressure fluid operated tool of the character referred to, the combination of a cylinder assembly, a handle assembly for said cylinder assembly, means for operatively connecting said assemblies for relative longitudinal movement therebetween, and shock absorbing means between said assemblies including longitudinally spaced external annular flanges on said cylinder assembly, a fluidtight sliding joint between said flanges and said handle assembly, a piston-like member carried by said handle assembly extending radially and inwardly therefrom between said flanges, and means for supplying fluid between said flanges at opposite sides of said piston-like member.

3. In a pressure fluid operated tool of the character referred to, the combination of a substantially cylindrical motor assembly, a supporting assembly for said motor assembly including a handle member fitted over one end portion of said motor assembly, means for operatively connecting said assemblies for relative longitudinal movement therebetween, and means for retarding said relative movement including a fluid chamber between said motor assembly and handle, a piston-like element carried by said handle member extending radially and inwardly therefrom into said chamber, a fluidtight joint between said motor assembly and handle member adjacent each end of said chamber, and a restricted fluid conduit connecting the portions of said chamber at opposite sides of said piston-like member.

4. In a pressure fluid operated tool of the character referred to, the combination of a cylinder assembly including a cup shaped member forming one end portion of said assembly, a supporting assembly for said cylinder assembly including a handle member fitted over said cup shaped member, means for operatively connecting said assemblies for relative longitudinal movement therebetween including a sliding joint between said members, and means for retarding said relative movement including a fluid chamber intermediate the ends of said sliding joint formed by a groove on the external wall of said cup shaped member covered by the inner wall of said handle member, a piston-like element carried by said handle member extending inwardly therefrom into said chamber, and a restricted fluid conduit connecting the portions of said chamber at opposite sides of said piston-like member.
